CLAIM

The ornamental design for a modular bulkhead, as shown and described.

DESCRIPTION

FIG. 1 is a perspective view of a modular bulkhead of the present invention.

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top view thereof;

FIG. 7 is a bottom view thereof; and,

FIG. 8 is a perspective view on a reduced scale thereof, with a multitude of like bulkhead components in broken lines.

The broken lines shown in the drawings are included for the purpose of illustrating environmental structures and form no part of the claimed design.
